JOIST

Edwin D. Coddington, Milwaukee, Wis., assignor
to Reynolds Corporation, New York, N. Y., a
corporation of Delaware

Application September 3, 1935, Serial No. 39,028

6 Claims. (Cl. 189—37)

The present invention has to do with a fabricated metal and concrete joist.

The objects of the invention include, among others, the provision of the following:

5 A skeletonized metallic joist into which nails may be driven and which possesses great strength with relatively low cost of manufacture; and

An improved reenforcing structure for a metal and concrete joist which may readily be substituted for a wood joist.

10 These objects, and such other objects as may hereinafter appear, are obtained by the novel construction, unique arrangement, and improved combination of the several elements which constitute the invention, one embodiment of which is illustrated in the accompanying single sheet of drawing, hereby made a part of this specification, and in which:

Figure 1 is a side elevation of a joist embodying the subject matter of the present invention;

20 Figure 2 is a transverse section on the line 2—2 of Figure 1;

Figure 3 is a transverse section on the line 3—3 of Figure 2;

25 Figure 4 is a transverse section on the line 4—4 of Figure 1; and

Figure 5 is a sectional detail taken on the line 5—5 of Figure 1.

Like reference numerals are used to indicate 30 similar parts in the drawing and in the description of the invention which hereinafter is given.

The improved joist herein described and illustrated comprises a top chord 10, a bottom chord 11, an end member 12, and an intermediate web member 13.

35 The top and bottom chords 10 and 11 are identical but reversed. Said members comprise a U-shaped channel member 14 of suitable metallic material having a narrow interior portion 15, a flaring side 16, and a second flaring side 17, the shape of which is reversed to that of the side 16. The sides 16 and 17 define at their edges flanges which terminate parallel to the transverse interior portion 15.

40 Across the open side of the channel member 14 is a flat sheet of material 18 generally of the same width as the channel member from the edge of one flange to the edge of the opposite flange. This closure member or flat strip of metal 18 is joined to the U-shaped member 14 along its edge by a series of spot welds or in any other suitable manner.

The two metal members comprising the parts

14 and 18 thus together define an elongated tube.

50 The opposite chord 11 of the joist is of an iden-

tical structure and comprises a channel member having a flat base, sides with flanges and a metal strip covering, the position of the parts being reversed to those of the first described chord 10. The first referred to U-shaped chord 10 and the 5 second referred to U-shaped chord 11 are each filled with cementitious material forming a core 20. This core may be composed of a mixture of gypsum, Portland cement and sawdust, represented in the proportions, by weight, 55:20:9. 10 This mixture is packed into the casings in a dry state and moisture then introduced through openings 19 (Fig. 2) formed in and throughout the length of the closure strip, to supply the necessary water of crystallization to harden the material. 15 This process of fabrication is described and claimed in my copending application Serial No. 39,022. Of course any other suitable fillers or processes of fabrication may be employed.

The U-shaped chords 10 and 11 are arranged 20 in parallelism with their ends terminating in alinement. The chords 10 and 11 are of predetermined standard lengths. An end member 12 is disposed at each end of the joist and intermediate the end members 12 is a reenforcing 25 and spacing web 13. The web comprises two elongated arcuate members oppositely disposed, the arcuate members being indicated 23 and 24 and being joined at their centers and contacting surfaces by spot welding 22 (Fig. 5). Members 30 23 and 24 after attachment one to another are folded at predetermined intervals along their length.

At the folded sections, the members 23 and 24 are flattened to provide a surface that will lie 35 flat against the inner sides of chords 10 or 11.

In the structure illustrated in Figure 1, obliquely disposed sections of web 13 are indicated by the numerals 25. The flattened out portions of the web 13 lying against the chord 11 are designated 40 26 and the flattened portions lying against the chord 10 are indicated 27. The length of the members 23 and 24 is determined by the length of the chords 10 and 11, and by the length of the end members 12 now to be described in detail. 45

The end members 12 overlie a flattened extension 28 of the web 13. Each end member 12 comprises an exposed side or end 30, a side 31 contacting the inner surface of chord 10, a side 32 at the interior of the joist, and a side 33 contacting the web extension 28. The sides 30, 31, 32, and 33 form a rectangle and will be ordinarily made of a single strip of material.

Two dish shaped members 36 and 38 having, respectively, peripheral flanges 37 and 39 are tele- 55

scoped into the opposite sides of the rectangular frame of the end member 12. Spot welding 40 may be used to maintain the member 36 in position. It is customary to fill member 12 with a 5 cementitious material which will receive nails driven thereinto, such concrete fill being indicated by the numeral 42. Member 38 is secured in position by spot welding 41 after the fill 42 has been inserted.

10 The joist generally is assembled by inserting between the chords 10 and 11 the web 13, and thereafter inserting the end members 12. All of the parts are secured in position by spot welding. Plate 36 is then fitted into position if not previously inserted and welded. As previously stated, end member 12 at its bottom side overlies a flat 15 end section 28 of the web 13. Member 12 is attached to chord 10 and web extension 28 by spot welding 43 and 44, and web 13 is secured to chords 20 10 and 11 by welds 45 and 46.

The fill for the end members 12 may be inserted after said members are spot welded to the chords 10 and 11, and chords 10 and 11 may be filled after all spot welding has been completed except 25 the welding of side piece 38 to member 12, which is attached after the fills are inserted.

The structure described is exceedingly strong. The web comprising opposed arcuate strips joined along their longitudinal lines and flattened out 30 at spaced intervals for attachment to chords 10 and 11 resists both compressing and torsional strains to a remarkable degree when the weight of the structure is considered. The chords and end members readily receive nails and may be 35 used as, and in place of wooden joists. The joist is simple to fabricate and the cost of assembly and materials is relatively low.

I claim:

1. A metal and nailable concrete joist comprising spaced apart composition filled chords, and a web therebetween comprising paired opposed arcuate members.

2. A metal and nailable concrete joist comprising spaced apart, nail receiving chords, and a web comprising a continuous strip of paired oppositely arranged arcuate members secured to said chords at spaced intervals. 5

3. A metal and concrete joist comprising spaced apart, nail receiving chords, and a web therebetween of obliquely-disposed, paired arcuate members joined one to another along their longitudinal median lines and engaging said chords 10 at intervals.

4. A metal and concrete joist comprising spaced apart, nail receiving chords, and a web therebetween, said web comprising paired, opposed strips engaging the chords at spaced intervals, the sections of said strips contacting said chords being flat and the intermediate sections of said web comprising opposed arcuate channels joined one to another along their longitudinal median lines. 15

5. A metal and concrete joist comprising channel shaped chords filled with a nailable composition, and a web therebetween, said web comprising paired longitudinal strips joined one to another at their longitudinal median lines, said strips having flat portions contacting the inner faces of 25 said chords, and being substantially X-shaped in cross-section between said contacting portions.

6. A joist comprising opposed U-shaped metal chords of channel shape covered with a metal strip at their edges and filled with a nailable composition, parallelopiped end members of metal and a nailable composition between said chords, and a web between said chords extending unbrokenly from one end member to the other end member, said web comprising a pair of elongated 35 strips arcuate in cross section and joined one to another at their longitudinal median line, said strips being folded alternately in one direction and then the other and being joined at succeeding folds to opposite chords. 40
